UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

SHEET-DELIVERY APPARATUS.

No. 834,791.

Specification of Letters Patent.

Patented Oct. 30, 1906.

Original application filed July 6, 1905, Serial No. 268,453. Divided and this application filed June 8, 1906, Serial No. 320,800.

To all whom it may concern:

Be it known that I, ALBERT B. DICK, a citizen of the United States, residing at Lake Forest, in the county of Lake and State of Illinois, have invented certain new and useful Improvements in Sheet-Delivery Apparatus, of which the following is a specification.

This invention relates to sheet-delivery apparatus adapted for use in connection with such devices as printing and folding machines.

The object of the invention is to effect certain improvements in the construction of such apparatus, more particularly with respect to the provision of various adjustments by means of which uniform and reliable operation can be obtained with sheets of various sizes.

I will describe my invention in connection with the accompanying drawings, which show the preferred embodiment thereof, and in which—

Figure 1 is a central section of a folding-machine provided with my improved delivery apparatus. Fig. 2 is a transverse section thereof. Fig. 3 is a section on line 3 3 of Fig. 2, and Fig. 4 is an elevation of a portion of one end of the machine.

Although I have shown my improved delivery apparatus in connection with a folding-machine, I wish it understood that it is equally well adapted for use in connection with machines of different character—as for instance, printing-machines.

The machine consists of two side plates A, on the upper edge of which is mounted a support B for a sheet-pile b', held in proper position by adjustable guides b². A hinged weight b³ bears on the top of the sheet-pile. Directly under this weight and mounted in bearings in the side frames of the machine are a separator-roll C and an idler-roll C', the former of which is rotated by any suitable mechanism to successively buckle the sheets of the pile between it and the idler-roll C'. Directly below these rolls are pressing and passing rolls D and D', rotatable in bearings in the frames A A, and directly below these rolls is another pair of pressing and passing rolls D² D³, which receive the sheet folded by the rolls D D' and pass it downward into the mouth of a guide E. This guide has an adjustable stop E' therein, which limits the movement of the sheet into the guide, buckles

the sheet, and causes it to pass out between the roll D² and a delivery-roll d, arranged adjacent to the pressing and passing roll D². A guide d' is mounted upon a shaft d² and extends in proximity to the point of contact of the rolls D² and d and is arranged to guide the forward edge of a sheet passing between those rolls downward and to be moved on its supporting-shaft by the sheet to permit the sheet to pass beyond the guide. Mounted directly below the end of the reciprocating guide d' is a guide-roll d³. This roll preferably has peripheral grooves therein, into which lips on the end of the reciprocating guide d' can enter when the end of the guide is moved downward by a sheet. These parts of the machine are described in detail in a companion application, Serial No. 268,453, of which this application is a division, this application being limited to the delivery apparatus, which may be used with any folding or printing machine.

Mounted vertically directly below the delivery-roll d is a stripper-plate F, the upper edge of which terminates either in contact with or in close proximity to the roll d. Formed on this plate are two vertical guides f and between these guides is a slot f². The supporting-frame G for the delivery-tray has ways therein, into which the guides f extend, and between these ways is a threaded opening adapted to receive the threaded end of a hand-nut f³, which extends through the groove f² in the stripper-plate F. In this way the frame G and the parts of the delivery-tray carried thereby can be moved to any desired position of vertical adjustment and then secured in that position by tightening the hand-nut f³. Pivotedly mounted in ears g, formed on frame G, are the ways H H of the delivery-tray, the rear ends of which extend through openings h in the stripper-plate F and are turned upwardly. Mounted for rotation in ears g' and g², formed on the frame G, is a shaft g³, on which is mounted a forwarding-roll g⁴, lying between the ways H H. On the end of shaft g³ beyond the side plate A is a spiral gear h', meshing with a similar gear h², splined upon a shaft h³. At its lower end this shaft is journaled in bearings formed in arms integral with the ear g² of frame G, one of these arms extending above and the other below the pinion h², and the shaft is arranged to freely slide axially in

these bearings. At its upper end shaft h^3 has secured thereto a spiral gear i , lying between the arms of a yoke i' , secured on the side frame A, which arms have bearings formed 5 therein for the shaft h^3 . The spiral gear i meshes with a similar gear i^2 , secured on a stub-shaft i^3 , carrying a gear i^4 , which meshes with a similar gear on one of the shafts of the machine. It will thus be seen that the driving 10 connection to the forwarding-roll g^4 is maintained in all positions of adjustment of the frame G and the parts carried thereby, the only effect of such adjustment, so far as this connection is concerned, being to move 15 the spiral gear h^2 , which is splined on shaft h^3 axially of that shaft. The periphery of the forwarding-roll g^4 extends slightly above the surface of the ways H H, so as to forward on the same the folded sheets fed thereon.

20 Formed in each of the frame members A A is an arc-shaped slot J, curved about the pivotal axis of the ways H H as a center, and within these slots operates a cross-rod j , one end of which is provided with a head j' and 25 the other end of which is threaded and provided with a hand-nut j^2 . This rod j extends through slots formed in brackets j^3 , each of which is secured to the under side of one of the ways H. The outer end of the ways can 30 thus be moved to any desired position by loosening the hand-nut j^2 and moving the rod j , which supports that end of the ways, to any position between the ends of the slots J, in which position the rod may be held by tightening the nut j^2 . The outer end of the delivery-tray, as well as the inner end, can thus 35 be adjusted as desired in order to obtain the position and inclination of the ways H which will give the best results.

40 Mounted to slide back and forth upon the ways H is a block K, which maintains the sheets in proper position upon the ways and is moved backward by the accumulation of the sheets between it and the stripper-plate F.

45 In the operation of the machine the sheets which have been folded or otherwise acted upon are passed between the rolls d and d^3 and down alongside the stripper-plate F, which in addition to guiding the sheets prevents them from being carried around by the 50 roll d . As the sheets accumulate upon the ways H they are moved along by the forwarding-roll g^4 , the periphery of which is fluted or corrugated, but are always maintained in proper position by the sliding block K. The position of the end of the ways adjacent to the roll d can be readily adjusted toward and from the roll d . The best 55 results are obtained when the delivery-tray is in such position that when the lower edge of the sheet reaches the ways H the upper edge has just passed below the line of engagement of the rolls d and d^3 , so that when the downward movement of the sheet is arrested 60 by the ways the roll d^3 will carry the upper

edge of the sheet around to the side of that roll away from the roll d . This provides a narrow V-shaped space into which the forward edge of the next sheet brought around by roll d can enter. By means of the adjustment provided for the end of the delivery-tray adjacent to roll d this position can be obtained for sheets varying considerably in size. The forwarding of the sheets along the delivery-tray is effected more or less readily, 70 dependent upon the character of the sheets themselves, and by adjusting the inclination of the tray this forwarding of the sheets can be retarded or assisted. Since provision is made for the adjustment of both the inner 75 and the outer ends of the tray, such inclination as will give the best results can be readily obtained.

Having now described my invention, what I claim as new therein, and desire to secure 85 by Letters Patent, is as follows:

1. In sheet-delivery apparatus, the combination of a delivery-roll, a stripper-plate co-acting therewith, a delivery-tray one end of which enters an opening in said stripper-plate, means for adjusting the end of said tray adjacent to said delivery-roll toward and away from the roll, and means for locking the tray in any adjusted position, substantially as set forth. 95

2. In sheet-delivery apparatus, the combination of a delivery-roll, a stripper-plate co-acting therewith, a delivery-tray one end of which enters an opening in said stripper-plate, and means for adjusting the ends of said tray relatively to said delivery-roll, one 100 independently of the other, substantially as set forth.

3. In sheet-delivery apparatus, the combination with a delivery-roll, of a delivery-tray, means for adjusting the ends of said tray relatively to said roll, one independently of the other, forwarding-roll in said tray, and means for driving said roll, substantially as set forth. 105

4. In sheet-delivery apparatus, the combination with a delivery-roll, of a delivery-tray adjustable toward and away from said roll, a forwarding-roll adjustable with said tray, and means for driving the same in any position of the adjustment of the tray, substantially as set forth. 110

5. In sheet-delivery apparatus, the combination with a delivery-roll, of a delivery-tray adjustable toward and away from said roll, a forwarding-roll mounted in bearings adjustable with said tray, and means for driving said forwarding-roll in any position of the adjustment thereof, substantially as set forth. 115

6. In sheet-delivery apparatus, the combination with a delivery-roll, of delivery apparatus including ways, means for adjusting said ways toward and from said delivery-roll, a forwarding-roll operating between said ways, a shaft driven from a source of power 125 120 125 130

common to said delivery-roll, and a sliding connection between said shaft and said forwarding-roll, substantially as set forth.

7. In sheet-delivery apparatus, the combination with a delivery-roll, of delivery apparatus including ways, means for forwarding sheets on said ways, a block mounted to slide on said ways, means for adjusting the inner end of said ways relatively to said roll, and an adjustment device coacting with the outer end of said ways, substantially as set forth.

8. In sheet-delivery apparatus, the combination of a delivery-roll, a stripper-plate coacting therewith and delivery apparatus including adjustable ways whose ends enter openings in said stripper-plate, and means

for locking said ways in any adjusted position, substantially as set forth.

9. In sheet-delivery apparatus, the combination of a delivery-roll, a stripper-plate coacting therewith, and delivery apparatus including ways whose ends operate in openings in said stripper-plate, and means for adjusting the inner ends of said ways relatively to said roll, substantially as set forth.

This specification signed and witnessed this 4th day of June, 1906.
